UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed May 28, 1925. Serial No. 33,352.

My invention relates to lasts, and particularly to collapsing lasts.

It is the object of my invention to provide a collapsing last with the parts pivotally mounted one on the other moving about a given center of movement with such parts connected together by a solid link, the ends of which are adapted to yield or open to permit the movement of the last parts from one position to the other and to hold them in a given position when so moved.

It is my object to provide a flat spring plate having such yielding ends as to permit of the movement of the last parts and to yieldingly resist such movement.

It is a further object to provide a straight plate link the ends of which permit of this yielding feature thus eliminating a spring.

It is a further object to mount this plate with the spring ends on anchor pins so arranged that a line drawn between the centers thereof will pass over the center of movement of the last parts when the parts are moved and the ends of the links are flexed.

25 Referring to the drawings:

Figure 1 indicates a preferred form of the last partially in section;

Figure 2 illustrates a modified form; and

Figure 3 illustrates another modification.

30 Referring to the drawings in detail, 1 is a toe part having a slot 2 for accommodating the link. The rear face of the toe part is designated 3. Located transversely of the rear face 3 of the last part 1 and across the opening of the slot 2 is a semi-circular groove 4 for receiving the projecting cylindrical shoulder or knuckle 5 carried by the heel part 6, on the forward face of this heel part which is vertical at 7 to form a shoulder 8 abutting against the shoulder 8 of the toe part, but this face is cut away at 9 to permit of the collapsing of the last parts. The heel part is provided with a slot 10 for receiving the link which consists of a flat plate having a central portion 11 and end portions which are mounted upon the anchor pins 12 and 13 extended transversely of the slots 10 and 2. These anchor pins are so located that a line drawn between the centers 35 thereof will be below the center of movement 14 when the parts are in expanded position and above such point when the parts are in collapsed position. The ends of the link are provided with Y-shaped slots 15, the base of the Y-shaped portions being di-

rected towards the center of the link which is solid, while the arms are spaced from and are located on either side of the respective anchor pins 12 and 13, there being sufficient solid material between the arms to form the bearing in the end of the link for the anchor pins. The material on either side of the Y-shaped arms is connected together by an end portion of the link material on the outside of the anchor pins designated 16 which forms a yielding bridge across the Y-shaped opening and a reinforcing abutment for the rear surfaces of the anchor pins.

It is obvious from an inspection of the drawings that when the parts move these ends of the links flex because of outward pressure of the anchor pins 12 and 13 against these slotted, spring-like ends sufficiently to permit of the movement over the dead center 14 so-called.

75 The link form shown in Figure 2 consists of a central portion 11 with enlarged heads 17 which have transverse, partially curved slots 18 which communicate with a right-angle, longitudinally located narrower slot 19 having a circular opening 20 at the other end of the slot 19 from the slot 18. The slot 18 is widened at the center thereof to accommodate the anchor pins 12 or 13. The bridge member end of the link 21 is convex to form a resisting spring bridge member. When the parts pass over dead center the line or distance between the centers of the anchor pins being lengthened by reason of the movement of the parts on the eccentrically curved co-operating faces 4 and 5 the end members 21 are flexed, which flexing causes the slots 19 to spring open. This yielding of the ends of the link permits of the movement of the parts from one position to the other.

90 Referring to Figure 3, there will be observed another form of link which consists of a plate link having a solid central portion 22 with enlarged heads 23 which are provided with a centrally located slit 24 which extends inwardly to the base of a V-shaped slot 25 in which is located the anchor pin. When the parts move over dead center this slit 24 opens by reason of the pressure of the pins 12 and 13 against each side of the ends 23, as will be apparent from an inspection of the drawing, and either side of the ends 23 is spread apart 95 or flexed yieldingly.

110

It will be understood that I desire to comprehend within my invention such modifications and changes as may be necessary to adapt it to varying conditions and uses.

Having thus fully described my invention, what I claim as new and desire to secure by Letters Patent, is:—

1. In a last having a toe part and a heel part adapted to rock upon one another about a given point, a link having an inflexible body connecting said parts together, said link having spring ends adapted to flex to permit the parts to move from one position to the other.
2. In a last having a toe part and a heel part adapted to rock upon one another about a given point, a link connecting said parts together, said link having spring ends adapted to flex to permit the parts to move from one position to the other, the center of said link being inflexible.
3. In a last having a toe part and a heel part adapted to rock upon one another about a given point, a link connecting said parts together, said link having spring ends adapted to flex to permit the parts to move from one position to the other, the center of said link being inflexible, said link consisting of a plate.
4. In a last having a toe part and a heel part adapted to rock upon one another about a given point, a link connecting said parts together, said link having spring ends adapted to flex to permit the parts to move from one position to the other, the center of said link being inflexible, said link consisting of a plate, said plate having slots

at either end thereof to permit of the flexing of the ends of the link.

5. In a last, a heel part and a toe part adapted to rock about one another about a given center of movement, a plate link of substantially rectangular form, anchor pins for the ends of said link, the ends of said link being arranged to yield and flex when the parts are moved from one position to the other.

6. In a last, a heel part and a toe part adapted to rock about one another about a given center of movement, a plate link of substantially rectangular form, anchor pins for the ends of said link, the ends of said link being arranged to yield and flex when the parts are moved from one position to the other, said flexing being permitted by slots cut in the ends of said link.

7. In a last, a toe part and a heel part adapted to rock one upon the other, a plate link connecting said last parts, anchor pins in said last parts for supporting the ends of said link, said link being provided at either end with a Y-shaped slot to permit the link to flex at its ends.

8. In a last, a toe part and a heel part adapted to rock one on the other, anchor pins in said last parts adapted to support a plate link, a plate link having Y-shaped slots in the ends thereof to permit the ends of the link to flex, said anchor pins being located in the jaws of the Y-shaped slots.

In testimony whereof, I affix my signature.

GEORGE CLAUSING,
